UNITED STATES PATENT OFFICE.

WILLIAM L. CALDWELL, OF CANTON, OHIO, ASSIGNOR TO THE BERGER MANUFACTURING COMPANY, OF CANTON, OHIO, A CORPORATION OF OHIO.

METAL STRUCTURE.

1,074,242.

Specification of Letters Patent. Patented Sept. 30, 1913.

Application filed November 27, 1911. Serial No. 662,567.

To all whom it may concern:

Be it known that I, WILLIAM L. CALDWELL, a citizen of the United States, residing at Canton, in the county of Stark and State of Ohio, have invented certain new and useful Improvements in Metal Structures; and I do hereby declare that the following is a full, clear, and exact description of the same, such as will enable others skilled in the art to which it pertains to make and use the same.

The present invention has relation to metal structures designed to be used in buildings and is calculated to take the place and be used instead of wood studding and joist.

The objects of the present invention are, first to provide a metal structure especially designed to hold in proper position the usual plaster board, or similar material, second, to provide means for securing the metal studding or structure in position with reference to the building. These objects, together with other objects, readily apparent to those skilled in the art, I attain by the construction illustrated in the accompanying drawings, although my invention may be embodied in a variety of other forms the construction illustrated being chosen by way of example.

In the accompanying drawings Figure 1 is a perspective view of the metal structure, studding or joist. Fig. 2 is a transverse section, showing two metal structures or studs in cross section and illustrating the plaster boards properly connected, the plaster boards being shown in section.

Similar numerals of reference indicate corresponding parts in all the figures of the drawings.

In the accompanying drawing, 1 represents a portion of one stud or joist or metal structure, which is formed of any desired length, reference being had to the particular use to which the stud, joist or structure is to be put.

In practice the metal studs, joist or structures are formed in predetermined lengths, which lengths are standard or practically so, but it will be understood that the metal structure may be formed of any desired length. For the purpose of providing means for securely holding the plaster boards 2 or their equivalents in proper relative position with reference to the metal

structure, the longitudinal edges of the structure are provided with the integral angled flanges 3, which flanges are for the purpose of providing suitable backing or rests for the plaster boards or their equivalents and upon which the backs of the plaster boards 2 or their equivalents are seated. The structure 1 is also provided upon its longitudinal edges with bendable tangs 4, which are located between the angled flanges 3.

In Fig. 1 I have illustrated a metal structure provided with angled flanges extended in opposite directions from the body of the structures. This construction being necessary when plaster boards or their equivalents are to be connected as illustrated in Fig. 2, but it will be understood that when plaster boards or their equivalents are to be connected upon one edge of the structure only, the angled flanges 3 are extended from one side of the structure only, but in any event the bendable tangs 4 are to be located alternately with reference to the flanges 3. For the purpose of adjusting the length of the stud, joist or metal structure so as to provide means for connecting the ends of the same the adjustable connecting plate or head 5 is provided, which connecting plate or head is provided with the elongated slot 85 6, through which the clamping bolt 7 is passed. The plate or head 5 is connected with the angled flange 8, which flange is for the purpose of making the proper connection by means of nails or their equivalents. For the purpose of increasing the rigidity of the stud, joist or structure 1, the body portion is corrugated as illustrated or more specifically provided with the curved portion 9. In the drawings, I have illustrated, a single curved portion, but it will be understood that more than one curved portion may be provided if desired, as the only object is to stiffen the structure.

In use the desired number of studs, joist or metal structures are placed in proper relative position and in the position usually occupied by the ordinary wood studding and joist. The plaster boards or their equivalents are placed in proper relative position and in such a position, that is to say, placed against the angled flanges after which the bendable tangs 4 are bent into the position illustrated in Fig. 2. It will be understood that by bending the tangs 4 in opposite di-

rections, the plaster boards or their equivalents will be held snugly against the flanges. 3. In use the plaster boards 2 are formed of such a size that they can be placed in proper 5 position with reference to their supports. It will be understood that if in the event plaster boards should be used they should be formed of such a predetermined size that a single board will fill the space between any 10 two studs, joist or metal structure, or the studs, joist or metal structures should be so spaced with reference to each other that the vertical edges of the plaster boards or their equivalents will be adjacent each other at or 15 near the parallel edges of the studs, joist or metal structure, so that by bending the bendable tangs in opposite directions the vertical edges of two plaster boards will be held at the places where the studs, joist or metal 20 structures are located. In the drawings I have illustrated the adjustable plate or head 5 located at the top or upper end of the stud or metal structure, but it will be understood that a duplicate head or plate may be located 25 at the bottom or opposite end of the stud as desired.

The structure is preferably formed of sheet metal and of a width equal to the width and lengths of the flanges and bendable tangs. The flanges and tangs are produced by cutting the body portion for a distance equal to the length of the flanges and bendable tangs, the cuts being made at right angles to the length of the body portion. 30

35 Having fully described my invention what

I claim as new and desire to secure by Letters Patent, is—

1. A metal structure of the character described formed from sheet metal and comprising an elongated main body portion provided at its longitudinal edge with transverse slits forming integral relatively broad flanges and integral relatively narrow bendable tangs, said flanges bent at substantially right angles to the main body portion and 40 said tangs normally lying in the same plane with the main body portion.

2. A studding of the class described, consisting of a metallic strip provided with a series of oppositely disposed slits extending 45 along the edges thereof, and forming a series of wings along said edges, certain of said wings being bent to extend at approximately right angles to the body of said studding, a portion of said bent wings extending in a 50 direction from the body of the studding opposite to that direction in which the remainder of said bent wings extend, the remainder of said wings being unbent and extending parallel with the horizontal plane 55 of the body of the studding, substantially as described.

In testimony that I claim the above, I have hereunto subscribed my name in the presence of two witnesses.

WILLIAM L. CALDWELL.
